Primary Examiner—Louis S. Zarfas*Assistant Examiner*—Gregory Andoll*Attorney, Agent, or Firm*—Natter & Natter**[57]****CLAIM**

The ornamental design for an anti-snore appliance, as shown and described.

DESCRIPTION

FIG. 1 is a perspective view of an anti-snore appliance showing my new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a sectional view thereof, the same being taken along the line 6—6 of FIG. 5; and,

FIG. 7 is a bottom view thereof.

The left side elevational view is a mirror image of the right side elevational view shown in FIG. 4 and the air passages shown in dashed lines do not form part of the design.
